US00D672371S

(12) **United States Design Patent**
Nakamura et al.

(10) **Patent No.:** US D672,371 S
(45) **Date of Patent:** ** Dec. 11, 2012

(54) **BOOM FOR CONSTRUCTION MACHINE**

(75) Inventors: **Takanobu Nakamura**, Hiroshima (JP);
Yasushi Shigenari, Hiroshima (JP);
Takanori Yamasaki, Hiroshima (JP)

(73) Assignee: **Kobelco Construction Machinery Co., Ltd.**, Hiroshima-Shi (JP)

(**) Term: **14 Years**

(21) Appl. No.: **29/429,894**

(22) Filed: **Aug. 17, 2012**

(57) **CLAIM**

The ornamental design for a boom for construction machine, as shown and described.

DESCRIPTION

FIG. 1 is a first perspective view of a boom for construction machine showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged left side view thereof;

FIG. 10 is an enlarged right side view thereof;

FIG. 11 is an enlarged cross-sectional view taken along line 11-11 in FIG. 3 thereof; and,

FIG. 12 is an enlarged cross-sectional view taken along line 12-12 in FIG. 3 thereof.

The portion shown by broken lines is for illustrative purposes only and forms no part of the claimed design.
